UNITED STATES PATENT OFFICE

92,074

DESIGN FOR A FLOOR PLATE

Gerald G. Greulich, Mount Lebanon, Pa.

Application February 6, 1934, Serial No. 50,647

Term of patent 14 years

To all whom it may concern:

Be it known that I, GERALD G. GREULICH, a citizen of the United States, and a resident of Mt. Lebanon, in the county of Allegheny and State of Pennsylvania, have invented a new, original, and ornamental Design for Floor Plates of which the following is a specification, reference being had to the accompanying drawing forming part thereof.

In the drawing:

Figure 1 is a plan view of a plate embodying the novel design of this invention.

Figures 2 and 3 are sectional views taken on the lines II—II and III—III, respectively, of Figure 1.

A dominant or characteristic feature of this design is the appearance resulting from the relative arrangement of the large elements to the small elements.

I claim:

The ornamental design for a floor plate as shown and described.

In witness whereof, I have hereunto set my hand.

GERALD G. GREULICH.
